UNITED STATES PATENT OFFICE.

HARRY C. IVES, OF BRIDGEPORT, CONNECTICUT.

TOY BOAT.

1,409,549.

Specification of Letters Patent. Patented Mar. 14, 1922.

Application filed February 13, 1920. Serial No. 358,469.

To all whom it may concern:

Be it known that I, HARRY C. IVES, a citizen of the United States, and resident of Bridgeport, in the county of Fairfield and State of Connecticut, have invented certain new and useful Improvements in Toy Boats, of which the following is a specification.

This invention relates to new and useful improvements in toy motor boats of the class designed to be operated by a clock spring movement.

Spring movements for toy boats of this class are most advantageously positioned in the bottom of a boat so as to better operate the propeller shaft which is necessarily positioned low in the hull. These movements so far as I am aware have thus far been more or less permanently secured to the bottom of the boat, which made it difficult to get at to remove for repairs, especially since the top or the deck of most all toy boats of this class are sealed to prevent water from leaking in.

The purpose of my invention, therefore is to improve upon toy boats of this class, having a covered deck, by providing an opening in the deck, having a removable cover to afford access to the inside of the hull and to make the movement detachable so that the same can be taken out through the said opening.

This allows the movement to be removed by the owner should it become broken or disabled, and likewise repaired by the owner and the life of the motor prolonged, whereas under the old construction in order to repair the boat it was necessary to return it to the factory, and in which case it was more of a task to get the movement out than it was to repair it.

With these and other objects in view the invention resides and consists in the construction and novel combination and arrangements of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the

several figures of the accompanying drawings forming a part of this specification, and upon which,

Fig. 1 shows a plan view of a destroyer type of toy motor boat.

Fig. 2 shows a central vertical section of the boat shown in Fig. 1.

Fig. 3 is a plan view of the clock spring movement attached to the bottom of the boat, and

Fig. 4 shows a detached side view of the removable cover portion of the deck of the boat, which includes two funnels and a conning tower.

Referring in detail to characters of reference marked upon the drawings, 5 represents the hull of the boat, 6 a bed portion on the inside of the central portion of the bottom to support the clock spring movement. 7 represents the main deck and 8 a raised portion of the deck surrounding the elongated opening 9 formed immediately above the movement and through which the same may be placed in or removed from the boat. A shouldered ledge 10 is formed around the top edge portion of the opening in the raised portion 8 of the deck to receive the detachable cover 11 placed thereon and so as to support the same in a way to snugly close the opening.

12 represents a support attached to the stern of the boat, and on which a rudder 13 is adjustably mounted. The propeller wheel 14 is positioned inside of the rudder support and between it and the end of the stern of the boat and is mounted upon a propeller shaft 15 journalled in the bearing 16 also secured to the wall of the stern of the boat. The inner end of the propeller shaft is bent to form a crank 17 which is detachably engaged by the driven arm 18 of the motor shaft 19 and whereby the crank shaft and propeller are rotated.

The spring movement includes upper and lower plates 20 and 21 supported by the several posts 22. 23 represents the winding stem that projects up into the hollow stack 24 of the cover and through which the movement is wound. 25 indicates the usual form of clock spring, connected with the winding stem and 26 a gear operated by the spring. 27 is a pinion on a second shaft which is operated by the spring gear and 28 indicates a second gear connected and operated by the pinion 27. This second gear in turn

drives a second pinion 29 with which is connected a bevelled pinion 30 that in turn meshes with and drives the pinion 31 on the motor shaft 19 bearing the arm 18 which 5 engages the before mentioned crank. This motor shaft is journalled in a depending bearing 32 of the top plate of the movement as will be clearly apparent from Figs. 2 and 3 of the drawings. An upwardly extended 10 flange 33 is formed on the rear end of the bed 6 and includes an elongated slot to receive the extended tongue 34 formed on the rear end of the lower plate of the movement and whereby that end of the movement is 15 secured. A long screw 35 extends through the forwardly extended portion of the lower plate 22 of the movement to secure it in position after the tongue of the rear end has been positioned in the slot. 20 From the foregoing construction it will be seen that the movement can be wound in the usual way by positioning a key in the open end of the stack to engage the upper end of the stem 23 of the movement. It will 25 also be apparent from the foregoing description that by removing the cover shown in Figs. 1, 2 and 4, the top end of the screw can be engaged and removed to release the movement and when released in this way the 30 stem of the movement can be engaged and the movement drawn slightly forward and then lifted out. The connection of the driving shaft of the movement with the propeller shaft is such as to permit them to be 35 readily engaged or disengaged to further permit of the removal of the movement.

Having thus described the invention, what

I claim and desire to secure by Letters Patent, is—

1. A toy motor boat including a hull and 40 covered deck having an opening in its top, a removable cover for said opening, a clock spring movement for operating the boat and adapted to be removed through the opening in said top, separable means upon one portion of the movement for engaging the boat, and a screw for detachably securing the movement in such engagement.

2. A toy motor boat including a hull and 45 covered deck having an opening in its top, 50 a removable cover for said opening having a hollow smoke stack therethrough, a propeller shaft positioned in the hull, a clock spring movement including a winding stem extended up in said stack, and means for 55 detachably securing said clock spring movement in the bottom of said boat, said means being readily accessible through said opening.

3. A toy motor boat including a hull and 60 covered deck having an opening in its top, a removable cover for said opening, a propeller shaft positioned in the hull, a clock spring movement detachably connected with the propeller shaft, means for the detachable 65 connection of one end of the movement to the hull, and a screw for the attachment of the opposite end of the movement to the hull.

Signed at Bridgeport, in the county of Fairfield and State of Connecticut.

HARRY C. IVES.
